CLAIM

The ornamental design for a keycard with indexing channels, as shown and described.

DESCRIPTION

FIG. 1 is a top view of a "keycard with indexing channels" showing our new design;

FIG. 2 is a front elevational view thereof;

FIG. 3 is a bottom plan view thereof; and

FIG. 4 is a rear elevational view thereof.

FIG. 5 is a left side elevational view thereof, the side opposite being a substantially mirror image.
